UNITED STATES PATENT OFFICE.

HUGH CHRISTISON, OF METHUEN, MASSACHUSETTS, AND CLARENCE L. NUTTING, OF SALEM, NEW HAMPSHIRE, ASSIGNEES TO ARLINGTON MILLS, OF LAWRENCE, MASSACHUSETTS, A CORPORATION OF MASSACHUSETTS.

METHOD OF REMOVING FREE SULPHUR FROM GREASE.

No Drawing.

Application filed June 3, 1921. Serial No. 474,850.

To all whom it may concern:

Be it known that we, HUGH CHRISTISON, a resident of the city of Methuen, in the county of Essex and State of Massachusetts, and CLARENCE L. NUTTING, a resident of Salem, in the county of Rockingham and State of New Hampshire, both citizens of the United States of America, have jointly invented new and useful Improvements in the Method of Removing Free Sulphur from Grease, of which the following is a description.

The grease contained in raw wool is intimately associated with some sulphur which is practically in such an elementary state as to behave as if chemically free; and when the grease in this condition is extracted from the raw wool without undergoing substantial change in its constitution, as may be done by employing for that purpose the naphtha solvent process, the free sulphur therein although present in relatively small quantity is sufficient to detract seriously, in certain cases, from the utility otherwise possessed by the grease itself.

The object of our invention therefore, is to remove from such grease or from any similar fatty matter in like manner circumstanced, the free sulphur associated therewith without injuriously affecting the useful qualities of the grease itself.

This result we accomplish by heating and preferably by boiling with accompanying agitation, the crude sulphur-containing grease in an aqueous solution of an alkali compound which under these conditions is capable of chemically taking up such sulphur to form therewith another water soluble compound, or other water soluble compounds, having the like alkali as its base, or as their bases, and by subsequently obtaining the purified grease by physical application of gravitational or centrifugal force to its mixture with the liquor constituted by the water holding in solution the alkali-sulphur compound or compounds formed as aforesaid, together with any other soluble residual matter incidentally present, whereby the separation of such grease and liquor is effected because of their differences in specific gravity.

Our invention may be best exemplified by the following efficient and satisfactory mode of procedure:

Into a boiler-tank, preferably heated by a steam coil which is provided with open jets, we introduce a volume of water equal to about twice the volume of grease to be treated; and when this water is hot we dissolve therein, for every pound of free sulphur contained in the grease, six pounds of sodium sulphite technically known as normal sodium sulphite. The crude grease in a melted state is then added to this solution and the whole batch thus constituted is boiled for half an hour while being agitated meantime either by the passage of live steam through it or by mechanical means. During this boiling the sodium sulphite combines with the free sulphur associated with the grease and is thereby converted into sodium thiosulphate which likewise remains dissolved in the water present.

When the boiling has ceased and the resulting emulsion is allowed to stand undisturbed the water with its soluble ingredients tends to gravitate out of it gradually and to settle below the grease from which such settled liquor may finally be drawn off. This separation is expedited by keeping the contents of the tank at a temperature as high as feasible without promoting the agitation accompanying boiling, and it is convenient to have the tank steam-jacketed for the purpose. Or better still, because capable of being accomplished in less time, the separation of the liquor from the grease may be effected by introducing the emulsion as hot as practicable into a centrifuge similar in construction and mode of operation to the well known machine for separating cream from milk by centrifugal action. Furthermore such separation by either of these means is also facilitated and accelerated, if preparatory thereto the emulsion has been slightly acidified, either by adding to it sodium hydrogen sulphite, commonly known as sodium bisulphite, or by blowing into it sulphur dioxide gas through the open jets of the coil previously used for steam heating, sufficient in quantity to cause the emulsion to yield an acid test to blue litmus paper.

But a persistent difficulty stands in the way of expeditiously separating from the grease the entire aqueous solution constituting the treating liquor in its ultimate state, owing to the fact that the grease itself ab-

sorbs a notable quantity of water which will not readily separate therefrom and which consequently in this case retains a proportionate amount of the soluble contents of 5 the liquor whereof it is a fractional part. Hence in order to reduce to a negligible quantity the remnant of sulphur compounds retained with the water thus absorbed, the grease, after the separation therefrom of 10 so much of the said liquor as can be first eliminated, needs to be subjected to successive aqueous washings and drainings. This further treatment may preferably be accomplished by employing for each of such subsequent washings a hot dilute solution of 15 sodium chloride in water which is likewise then allowed to settle and run off, or is introduced into a centrifuge to effect an equivalent result, and finally the grease thus purified is dehydrated to substantially the minimum of its water of absorption, either by 20 having hot air blown through it or by submitting it to the mechanical action of a centrifugal separator.

25 Although according to established chemical relations one pound of free sulphur requires no more than four pounds of sodium sulphite to exhaust it in combining therewith to form sodium thiosulphate, yet experience has shown that in practising our 30 invention the best results are obtained when provision is made for the presence in the treating liquor of as much as one hundred and fifty per cent of the amount of sodium 35 sulphite theoretically needed for conversion into sodium thiosulphate by combination with all the free sulphur contained in the grease to be treated. This excess is highly desirable because without it there would apparently be difficulty in bringing about a 40 reaction thorough enough to induce all of the free sulphur present in the grease undergoing treatment to enter into chemical combination, and at any rate because such 45 complete exhaustion of the free sulphur would unduly prolong the operation of the process if much less additional sodium sulphite were used, notwithstanding that a corresponding surplus of the latter must remain unchanged in the liquor ultimately 50 separated from the grease.

The process already hereinbefore specifically described may be practised in a somewhat indirect mode by the preliminary 55 employment of certain chemical reagents which upon being brought together in aqueous solution under suitable conditions result in the ultimate production of a liquor containing sodium sulphite and likewise capable of being used for the treatment of sulphur-containing grease to effect its purification. Such a treating liquor sufficient in quantity to deal with one thousand pounds of grease containing three per cent in weight of free sulphur, may be prepared in

accordance with either of the following recipes designated respectively A, B, C and D, to wit:

A. 57 pounds of sodium hydroxide, commonly known as caustic soda, together with 70 450 pounds of commercial bisulphite of soda solution which usually contains about twenty per cent in weight of sulphur dioxide, are dissolved in 80 gallons of hot water.

B. 114 pounds of sodium hydroxide are 75 dissolved in 120 gallons of hot water, and to this solution are added 91 pounds of sulphur dioxide gas by being blown into it through a suitable perforated coil of pipe.

C. 75 pounds of anhydrous sodium carbonate, or else 120 pounds of sodium bicarbonate, are dissolved in 80 gallons of hot water and to either of these solutions are added 450 pounds of commercial bisulphite of soda solution constituted as aforesaid. 80

D. 150 pounds of anhydrous sodium carbonate, or else 240 pounds of sodium bicarbonate, are dissolved in 120 gallons of hot water, and to either of these solutions are added 91 pounds of sulphur dioxide gas by 90 being blown into it in the manner aforesaid.

Other sodium salts formed by combination with acids which are respectively soluble in water and weaker than sulphurous acid, such as for example tri-sodium phosphate, may be substituted in proper quantity for sodium carbonate or bicarbonate in either of the foregoing recipes designated 95 C and D.

Precaution should be taken that the liquid prepared in accordance with either of these 100 recipes suitable for employment in the practise of our invention by indirect mode of procedure does not show an acid reaction when tested with litmus paper. If it should 105 do so, a sufficient quantity of caustic alkali ought to be added to correct such acidity; but on the other hand an excess of alkalinity should be avoided, for it is desirable that the condition of the liquor thus prepared 110 should approximate as nearly as possible to that of the liquor produced by dissolving in hot water at the outset neutral sodium sulphite already formed, as in the direct mode of procedure first hereinabove described. 115

Into the liquor resulting from conformity to either of the foregoing recipes designated as suitable for pursuing an indirect mode of procedure, the one thousand pounds of 120 grease containing three per cent in weight of free sulphur already mentioned are introduced and thereupon the whole batch thus constituted is kept boiling and agitated for half an hour during which operation the sodium sulphite resulting from the 125 chemical reactions of the ingredients originally brought together in solution according to the recipe followed for producing the said liquor will have been converted into so- 130

dium thiosulphate by combining with the free sulphur contained in the grease, as far as the quantity of such free sulphur suffices for that combination.

5 The subsequent steps of the process are those which succeed to the corresponding stage of what constitutes the direct mode of procedure first hereinabove described.

Theoretically and doubtless actually in 10 the course of the chemical reactions involved in realizing each of the several modes of procedure herein set forth to exemplify our invention, sodium sulphite is the preponderant reagent by means of 15 which the free sulphur originally contained in the grease is ultimately incorporated and sodium thiosulphate the principal resultant product of such incorporation; but the prolonged duration of the process in each instance tends to induce between the constituent ingredients of the treating liquor various further chemical reactions which probably result in the formation of relatively small quantities of dithionic, trithionic, 25 tetrathionic or pentathionic acid and of corresponding sodium polythionates. Such additional variant compounds however like the sodium thiosulphate will have been produced at the expense of the free sulphur 30 eliminated from the grease, and will have been dissolved in the water of the treating liquor ultimately separated from the grease thus purified.

Thus far, sodium has been the only base-forming element specifically mentioned in connection with the chemical compounds employed and produced in the aqueous solution with which the grease containing free sulphur is treated in the described modes of 35 procedure embraced in our invention; and sodium is practically the most available base-forming element for such industrial purposes; but it should be understood that the corresponding compounds of potassium 40 and ammonium are equivalent substitutes 45 therefor.

We claim:

1. The method of removing free sulphur from grease by heating and simultaneously 50 agitating their mixture with an aqueous solution of a neutral alkali-sulphite in sufficient quantity to exhaust such free sulphur by chemically uniting therewith to become converted into a thiosulphate of the same alkali, and by subsequently separating the 55 grease from the water holding in solution the alkali-thiosulphate thus formed, by means adapted to effect their assumption of relative positions according to their respective differences in specific gravity.

2. The method of removing free sulphur from grease by boiling and agitating their

65 mixture with an aqueous solution of neutral sodium sulphite in sufficient quantity to exhaust such free sulphur by chemically uniting therewith, to become converted into sodium thiosulphate, and by subsequently separating the grease from the water holding in solution the sodium thiosulphate thus formed, by means adapted to effect 70 their assumption of relative positions according to their respective differences in specific gravity.

3. The method of removing free sulphur 75 from grease by heating and simultaneously agitating their mixture with an aqueous solution of a neutral alkali-sulphite in quantity somewhat more than theoretically sufficient to exhaust such free sulphur by chemically uniting therewith, and by subsequently separating the grease from the water holding in solution the resulting and residual alkali-compounds, by means adapted to effect their assumption of relative positions according to their respective differences in specific gravity.

4. The method of removing free sulphur 80 from grease by boiling and agitating their mixture with an aqueous solution of neutral sodium sulphite in quantity somewhat more than theoretically sufficient to exhaust such free sulphur by chemically uniting therewith, and by subsequently separating the grease from the water holding in solution the resulting and residual sodium compounds, by means adapted to effect their assumption of relative positions according to their respective differences in specific gravity.

5. The method of removing free sulphur 85 from grease, by heating and simultaneously agitating their mixture with an aqueous solution of a neutral alkali sulphite in sufficient quantity to exhaust such free sulphur by chemically uniting therewith, and thereupon by acidifying with sulphurous acid 90 the emulsion resulting from this purifying treatment of the grease in order to facilitate its separability from the treating liquor 95 and the soluble contents thereof.

6. The method of removing free sulphur 100 from grease, by boiling and agitating their mixture with an aqueous solution of neutral sodium sulphite in sufficient quantity to exhaust such free sulphur by chemically uniting therewith, and thereupon by solidifying with sulphurous acid the emulsion resulting 105 from this purifying treatment of the grease, in order to facilitate its separability from the treating liquor and the soluble contents thereof.

HUGH CHRISTISON.
CLARENCE L. NUTTING.

Certificate of Correction.

It is hereby certified that in Letters Patent No. 1,561,911, granted November 17, 1925, upon the application of Hugh Christison, of Methuen, Massachusetts, and Clarence L. Nutting, of Salem, New Hampshire, for "Methods of Removing Free Sulphur from Grease," an error appears in the printed specification requiring correction as follows: Page 3, line 116, claim 6, for the word "solidifying" read *acidifying*; and that the said Letters Patent should be read with this correction therein that the same may conform to the record of the case in the Patent Office.

Signed and sealed this 15th day of December, A. D. 1925.

[SEAL.]

WM. A. KINNAN,
Acting Commissioner of Patents.
